[57] CLAIM

The ornamental design for a sampling adapter for carbon dioxide monitoring in a respiratory system, as shown.

DESCRIPTION

FIG. 1 is a perspective view of a sampling adapter for carbon dioxide monitoring in a respiratory system, showing our new design;

FIG. 2 is a side elevational view thereof;

FIG. 3 is a front elevational view thereof;

FIG. 4 is a top plan view thereof;

FIG. 5 is a side elevational view thereof, opposite that shown in FIG. 2;

FIG. 6 is a rear elevational view thereof; and

FIG. 7 is a bottom plan view thereof.

The tube portion is fragmentarily shown in FIGS. 2, 3, 5, 6 and 7 for ease of illustration.
